Patented Apr. 6, 1926.

UNITED STATES PATENT OFFICE.

HASBROUCK J. WILLIAMS, OF BREVARD, NORTH CAROLINA.

RESISTING SAFETY LANDER FOR AERIAL MACHINES.

Application filed September 3, 1925. Serial No. 54,288.

To all whom it may concern:

Be it known that I, HASBROUCK J. WILLIAMS, a citizen of the United States, residing at Brevard, in the county of Transylvania and State of North Carolina, have invented certain new and useful Improvements in a Resisting Safety Lander for Aerial Machines, of which the following is a specification.

10 The present invention relates to a device for providing a safety landing of aerial machines generally, and particularly aeroplanes. The device is in the general form of a folded parachute carried on one of the 15 planes of the aeroplane so as not to interfere with the proper normal function thereof. The device has incorporated therein means whereby the parachute-like structure may be brought into active operation, 20 and function as the ordinary parachute, so that the aeroplane may fall slowly to the ground.

A very important object of the invention is to provide a device of this nature having 25 an exceedingly simple construction, one which is thoroughly reliable and efficient in use and operation, one which is strong, durable, inexpensive to manufacture, not likely to easily become out of order, easy to manipulate, and otherwise well adapted to the purpose for which it is designed.

With the above and numerous other objects in view as will appear as the description proceeds, the invention resides in certain novel features of construction, and in the combination and arrangement of parts 35 as will be hereinafter more fully described and claimed.

In the drawing:—

40 Figure 1 is a top plan view of an aeroplane with my improved structure incorporated thereon.

Figure 2 is a side view thereof, showing a 45 part in a vertical longitudinal section therethrough.

Figure 3 is a plan view showing the arcuate ribs of the device extended, and

Figure 4 is a fragmentary plan view showing the bows partly folded.

50 Referring to the drawings in detail it will be seen that an ordinary aeroplane of the bi-plane type has been shown in the drawing, and any other suitable aerial vehicle may be substituted therefor. The 55 aeroplane shown consists of a fuselage having the upper plane 6, and the lower

plane 7 associated therewith in the usual manner. A bracket 8 is mounted in the bottom of the fuselage, and has journalled therein a shaft 9 operable through crank 10. On this shaft within the bracket 8 there is fixed a drum 11 having a cable 12 wound thereabout. A tubular casing 13 rises from the bracket 8 and is braced by suitable guy wires 14 fixed to the bottom of the fuselage as at 15. An inwardly projecting flange 16 is provided at the upper end of the tubular casing 13. A rod 17 is slidable in the casing 13 and intermediate its ends is provided with a fixed collar 18. A coil spring 19 is disposed about the rod between the bracket 8 and the collar 18 and normally tends to extend the rod which is held retracted in the casing by the cable 12 wound about the drum 11. A collar 20 is disposed on the rod below the flange 13 and a spring 21 has one end fixed thereto, while the other end is fixed to the fixed collar 18 so that when the spring 19 expands to project the rod 17 from the casing 13, the loose collar 20 abuts the flange 16 so that the spring 21 will function as a buffer.

80 A head 22 is formed on the outer end of the rod 17. A pair of fixed arms 23 extend from opposite sides of the head 22 in offset relation as is clearly shown in Figure 4, and have buffer elements 24 on the ends thereof. In the present embodiment of the invention four arcuate ribs are attached to the head 22. Two of the arcuate ribs are indicated 85 generally by the letters A, and the other two of the arcuate ribs are indicated generally by the letters B. Each arcuate rib A includes a fixed section 25 radiating from the head 22 at right angles to the arms 23, and terminates in an offset stop 26. A section 27 is engaged with the outer end of the section 25 by a ring hinge 28. The section 27 terminates in an offset stop 29. A section 28 is engaged with the end of the section 27 by a ring hinge 30. A spring 31 is fixed to section 25, and a spring 31 is fixed to the section 27. The section 28 pulls over upon the section 27 as is shown in Figure 4, and the sections 28 and 27 when thus folded, fold upon the section 25. The springs 31 have a tendency to unfold these arms so that they will swing to an aligned extended position as shown in Figure 3. Each arcuate rib B consists of a section 32 which is connected to the head 22 by a ring hinge 33, a section 27' is hinged to section 32, and a section 28

is hinged to section 27'. Sections 27' and 28' are similar in construction to sections 27 and 28 respectively so that no further detailed description thereof is necessary. Springs 31 are associated with the sections of arcuate ribs B in the same manner that they are associated with the sections of the arcuate rib A. Section 28' of each arcuate rib B is adapted to fold upon section 27', and these sections 27' and 28' when folded upon each other are adapted to be folded upon the sections 32, and then the three sections 27', 28' and 32' are adapted to be folded over upon one of the sections 25. Springs 34 are provided on sections 25, and tend to push the folded sections of arcuate ribs B thereaway from, so that sections 32 will abut the buffers 24 of arms 23. The various sections of the arcuate ribs are held in the folded positions indicated to advantage in dotted lines in Figure 1 by cables 35 attached to the extremities of the end sections 28 and 28'. These cables are trained through suitable eyelets 36 provided on the head 22 and extend down alongside the tubular casing 13 and may be held in any suitable manner in the fuselage 5 so that when they are released, the various springs 31 and 34 will be brought into play to extend the sections of the arcuate ribs.

A cover 36' preferably constructed of oiled silk is attached to the end sections 28 and 28' in any suitable manner. When the sections of the arcuate ribs are folded, the cover is folded on the upper plane 6 as is indicated to advantage in Figures 1 and 2. When in this folded position, a shield 37 prevents the same from interfering with the proper functioning of the plane 6. This shield 37 is hingedly associated with the forward edge of the plane by spring hinges 38 so that the same will be pushed out of the way when the arcuate ribs are extended as previously indicated. By pulling upon the cables 35 the arcuate ribs may be folded with the cover and the rod 17 may be retracted in the casing by winding the cable 12 on the drum 11.

It is thought that the construction, oper-

ation, and advantages of the invention will now be clearly understood without a more detailed description thereof. The present embodiment of the invention has been disclosed merely by way of example, and in practice attains the various features of advantage enumerated as desirable in the statement of the invention and the above description. It is apparent that numerous changes in the details of construction, in the sizes, in the materials, and in the combination and arrangement of parts may be resorted to without departing from the spirit or scope of the invention as hereinafter claimed or sacrificing any of its advantages.

Having thus described the invention, what I claim as new and desire to secure by Letters Patent is:

1. In combination, an aerial vehicle including a fuselage, and a plane, a tubular casing extending upwardly from the fuselage through the plane, a rod slidable in the tubular casing, spring means normally holding said rod extended, buffer means associated with said rod, a head on the upper end of said rod, arcuate ribs extending from said head formed in foldable sections, means normally holding said sections extended, means for folding the sections, a cover associated with the sections.

2. In combination, an aerial vehicle including a fuselage, and a plane, a tubular casing extending upwardly from the fuselage through the plane, a rod slidable in the tubular casing, spring means normally holding said rod extended, buffer means associated with said rod, a head on the upper end of said rod, arcuate ribs extending from said head formed in foldable sections, means normally holding said sections extended, means for folding the sections, a cover associated with the sections, and a shield having a spring hinged connection with the forward edge of the plane for preventing the folded sections and cover from interfering with the proper operation thereof.

In testimony whereof I affix my signature,

HASBROUCK J. WILLIAMS.
